RECORDING DEVICE FOR CONCRETE
MIXING DRUMS

Raymond G. Osborne, Los Angeles, and Robert O. Boykin, Glendale, Calif., assignors, by direct and mesne assignments, of one-fourth to said Raymond G. Osborne, one-fourth to Raymond G. Osborne, Jr., one-fourth to Howard S. Osborne, and one-fourth to Philip S. Osborne

Application February 5, 1952, Serial No. 269,938

14 Claims. (Cl. 259—175)

1

This invention pertains to means and methods of accurately controlling and recording mixing conditions of concrete so as to insure the delivery of concrete in proper condition to a job.

In recent years large quantities of concrete have been delivered to job sites from central proportioning plants by means of vehicles provided with mixing devices, the sand, gravel, cement and water being usually mixed in such a device during transit from the central plant to the job site where the concrete is to be poured. Although the proportions of sand, gravel, cement and water are carefully measured by weight into the mixer carried by the vehicle, the rate of rotation of the mixer during transit, as well as the total time consumed during transportation from the central plant to the job, can vary appreciably. It is well known that rotation of a mixing drum at a low rate of speed results in poor mixing of concrete with consequent low concrete strength, while rotation at too fast a rate of speed creates a centrifugal force which prevents proper cascading and uniform mixing of the concrete which again reduces the structural strength of the resulting concrete. It is well understood that the rate of rotation of the mixer is an important factor; every mixing device has an optimum rotation speed at which the contents are more thoroughly agitated and more homogeneously mixed than at other speeds.

Heretofore, no means were provided to positively factually establish firm data pertaining to the actual number of minutes of mixing of each batch of concrete as well as the rate of mixing speed of the mixer drum minute by minute. The operator of the vehicle may have consumed a long period of time in moving the batch to the job or a short period of time; he may have run the mixer at one speed or another; the mixer may have run at an excessive speed for a certain time interval and was stationary during another period of time. As a result, one batch of concrete may have been properly mixed and may show the desired slump consistency whereas another batch may have been improperly mixed and have failed to develop desired workability and plasticity.

The present invention is directed toward means and methods whereby the inspector on the job is supplied with a positive record of the precise conditions of time and rate of rotation of the mixer, so that the characteristics of the concrete being delivered to the job are known. Moreover, the present invention provides a complete record upon which all essential data regarding the con-

2

crete, the mix used, the manner and time of mixing and other details are presented, thereby eliminating arguments and insuring the utilization of only acceptable concrete of a uniform character.

3 An object of the present invention, therefore, is to disclose and provide a simple and efficient means whereby an accurate record of mixing times and conditions are attained.

Another object of the present invention is to 10 design a device for providing such a record of mixing times and conditions which may be readily associated with rotatable mixing drums of various shapes and sizes.

A further object of this invention is to design 15 and provide a device as above described which may be driven by a rotatable mixing drum and which is provided with means for making a foolproof record of the time periods during which the mixing drum is rotated at a preselected desired speed.

Still another object of this invention is to design and provide a device as above described which includes intermittently actuatable switch means which are cooperable with other switch 20 means actuated only when the mixing drum is rotated at a preselected speed for recording time periods during which said mixing drum was so rotated.

Generally speaking, this invention contemplates a device for measuring and recording the 25 time periods during which a mixing drum rotates at a preselected desired speed, said device being adjustably mounted adjacent to the mixing drum. The device may comprise a hollow rotatable housing enclosing a speed responsive means 30 which is axially movable and driven by contact of the device with the surface of the mixing drum. An intermittently actuatable switch means is also carried within the housing and operable by rotation of the housing. The speed responsive means may carry a switch actuator means which is cooperable with a selectively positionable switch means for completing, together with the intermittently actuatable switch means, a circuit when the mixing drum is rotating at a 35 preselected speed. This circuit, when complete, causes actuation of a marking means for indicating on a time driven chart, the time periods at which the mixing drum was rotating at a selected speed, speeds which were too slow or too fast, and a stop condition. The time driven chart may be suitably located in the cab of the truck carrying the mixing drum. In one embodiment of this invention a foolproof record of the time 40 periods during which the drum was rotating at a

desired selected speed is made by burning such a record on the chart by means of suitably arranged spark coils.

Other objects and advantages of this invention will be readily apparent from the following description of the drawings.

In the drawings:

Fig. 1 is a side elevational view of a well-known type of mixing truck capable of mixing a batch of concrete while in transit.

Fig. 2 is a fragmentary end view of a device embodying this invention showing a mounting of the device to the frame of the truck and the device in rolling contact with the mixing drum.

Fig. 3 is a fragmentary side view of the device shown in Fig. 2.

Fig. 4 is an enlarged sectional view of the device shown in Fig. 3, the section being taken in a vertical plane passing through the axis of said device.

Fig. 5 is a fragmentary view taken from a transverse plane indicated by line V—V of Fig. 4.

Fig. 6 is a fragmentary view partially taken in the plane indicated at line VI—VI of Fig. 4.

Fig. 7 is an enlarged fragmentary view in section showing the means for axially adjusting one of the switch means.

Fig. 8 is a fragmentary view illustrating the speed responsive device in the preselected speed position wherein the adjustable means is closed.

Fig. 9 is a fragmentary view of the speed responsive device illustrating its position at a speed lower than a desired selected speed of rotation of the mixing drum.

Fig. 10 is a diagrammatic view illustrating a circuit means for actuating the recording means.

Fig. 11 is a view of one side of a recording chart used with this device for recording pertinent data relating to the batch of concrete being moved in transit.

Fig. 12 is a diagrammatic view of a circuit means for actuating a modification of the recording means wherein spark coils are used to burn the record on a recording chart.

Fig. 13 is a fragmentary view of a chart illustrating the pattern in which the burned record is made.

Fig. 14 is a diagrammatic view of a different modification of the circuit means for producing a record of the operation of a concrete mixer.

Fig. 15 is a diagrammatic view of a circuit means and recording means so that operational data concerning the job site concrete mixer may be recorded.

It has been found that to properly mix the sand, aggregate, cement and water so that acceptable concrete will be delivered to the job, an exemplary mixing drum of 4 to 5 yards capacity has an optimum peripheral speed of about 200 feet per minute. This speed should be achieved for an aggregate time period of from 12 to 16 minutes, the total time period being made either by one continuous time period or by a plurality of shorter time periods which aggregate 16 minutes. To deliver properly mixed acceptable concrete to a job, it is important that the driver be provided with information as to the time periods when the mixing drum is rotated at selected optimum speed so that the mixing may be completed when he arrives at the job. Also a permanent foolproof record of the mixing times and condition is of importance to insure that non-acceptable concrete is not used and to prevent and resolve any arguments as to mixing conditions.

Generally speaking, the device 19 of the present invention includes a rotatable hollow housing 20 supported for rolling contact with a peripheral surface of a mixing drum 21. Speed responsive means generally indicated at 22 are driven within housing 20 and carry a switch actuator means 23 for cooperable contact with a selectively adjustable switch means 24. Also within the housing is an intermittently actuated switch means 25 which is cooperable with the switch means 24 for closing and completing a circuit for causing actuation of a marking means generally indicated at 26. The marking means 26 records on a removable chart 25 which is rotatably driven by a suitable spring-actuated time clock 28 (Fig. 12), the chart, marking means, and time clock being carried within the cab of the truck.

In Fig. 1 is illustrated a truck carrying a concrete mixing drum 21 of well known construction and operation. The drum 21 is rotatable about an inclined axis and may be supported from a suitable frame 29 carried by the bed 30 of the truck. An engine 31 drives said mixing drum 21 through a gear arrangement generally indicated at 32. The rate of rotation of the drum may be controlled by suitable means by the driver from within the cab of the truck.

The device 19 embodying this invention may be carried by the frame 29 by a bracket 33 secured to an adjacent frame member by a suitable nut and bolt assembly 34. The bracket 33 includes an out wardly projecting portion 35 having a circular bearing face 35a for engagement with a bearing face 36 provided on a corresponding offset portion 37a on a coupling member 37. The off-set portions 35 and 37a may be pivotally connected by a suitable center pin and key assembly 38. The coupling member 37 includes an end element 39 lying in a plane at right angles to said faces 35a and 36 for connection to a hollow box-like member 40. The member 40 pivotally carries a U-shaped yoke 41 by means of a pivot rod 42 extending through a pair of upstanding spaced lugs 43 on said yoke 41 and suitably aligned openings 44 provided in said member 40.

The yoke is adjustably spring-biased against mixing drum 21 by means of a spring 45 connected at one end as at 46 to a bracket 47 carried by yoke 41. At its other end, spring 45 may be connected to a threaded adjusting rod 48 which is carried by a lug 49 connected to the member 40.

The generally cylindrical housing 20 may be supported between a pair of spaced opposed leg members 50 forming the yoke 41. The housing 20 (Fig. 4) may be formed of two housing portions 51 and 52 adapted to be joined adjacent the mid-section of the housing. Each housing portion 51 and 52 includes a radially outwardly extending annular flange 53 and 54 respectively secured together by any suitable means such as circumferentially spaced bolt and nut assemblies (not shown). Mounted on flanges 53 and 54 may be a rubber tire 55 adapted to contact as at 56 an outer peripheral surface of mixing drum 21.

The housing portion 51 is provided with an axially extending annulus 57 adapted to be received within a cooperative internal recess 58 on the housing portion 52 for positively positioning said portions in axial alignment.

At one end of housing 20 a stub axle 60 may be fitted in end wall 61 of housing portion 52 as at 62. The outer end of axle 60 may be journally supported by the adjacent leg member 50 of the yoke 41.

At the other end of housing 20, housing portion 51 may be provided with an end wall 63 having an inwardly extending internal annular boss 64 affording a seat as at 65 for a bearing means 66. Spaced from end wall 63 may be an annular partition wall 67 fitted as at 68 to a complementary interior surface on housing portion 51. The wall 67 is provided with an axial opening 69 within which is received and fitted a suitable bearing means 70.

The bearing means 66 and 70 support a hollow stub axle 71, the outer surface of said hollow axle 71 being formed with an intermediate shoulder 72 for spacing said bearing means 66 and 70. The outer end of the hollow axle 71 may be received within suitable journal means provided in the adjacent leg 50 of the yoke 41.

Speed responsive means 22 are axially carried and driven within housing 20 by a governor shaft 74 journally mounted at opposite ends by bearing means 75 carried within a central opening in a partition 76 fitted in housing portion 51 and by a bearing means 77 carried in a central opening of a partition 78 fitted within housing portion 52. The shaft 74 includes an extension 79 upon which may be mounted a gear 80 for rotatably driving shaft 74. The gear 80 may be meshed with a spur gear 81 carried by a stub shaft 82 antifrictionally supported as at 83 and 84 in partitions 76 and 67 respectively. The stub shaft 82 carries at its outboard end a gear 85 meshed with a stationary gear 86 carried by shoulder 72 of the hollow stationary axle 71 and secured against a radially outwardly extending flange 87 formed on axle 71.

The speed responsive means also includes a well known type of governor arrangement comprising a pair of oppositely disposed, radially movable governor weights 90, each pivotally connected to adjacent governor members 91, and 92 by means of pairs of links 93. Governor member 91 may be secured to shaft 74 for non-axial movement, while member 92 is slidable axially along shaft 74 in response to position changes of weights 90 caused by centrifugal forces acting thereon when rotating at different speeds. Fig. 4 shows the speed responsive means positioned when rotating at a relatively high speed, Fig. 9 shows the speed responsive means at a relatively low speed and Fig. 8 shows the position of the speed responsive means at a pre-selected speed.

The governor member 92 includes a tubular extension 94 provided with a shoulder for positioning ball bearing means 95 thereon. A retainer ring 96 secures said bearing means 95 against the shoulder. The outer race of the bearing means 95 carries the switch actuator member 23 which is virtually nonrotatable when the speed responsive means is rotated. The switch actuator member 23 comprises longitudinally oppositely tapering outer annular surfaces 97 which converge at the midportion of the actuator 23 to form a circumferential portion of maximum diameter so as to provide operable contact as at 100 (Fig. 8) with a roller element 101 of switch means 24. Thus, when the speed of rotation of the housing is that which has been selected, actuator 23 will depress roller element 101 for closing electrical contacts (not shown) provided by switch means 24.

Means for adjustably and selectively positioning switch means 24 for actuation at preselected speeds of rotation of housing 20 may include a threaded adjustably rotated shaft 103 provided

with threaded engagement with a member 104 carrying switch means 24. The shaft 103 may be suitably journaled as at 105 in a plate 106 carried by the axially extending flange 57 on housing portion 51. The opposite end of the shaft 103 may carry a pinion gear 107 on the outboard side of the partition 78 for connection to position indicating means for the switch means 24.

10 The pinion gear 107 meshes with a spur gear 109 carried by a stub shaft 110 mounted in partition 78. The stub shaft 110 carrying spur gear 109 also carries outboardly thereof gear 111 which meshes with a relatively large diameter gear 112 carried by an inboard extension 113 of stub axle 60. The outboard face of gear 112 carries a suitable circular disc 114 having on its outboard circumferential margin a plurality of indicia 115 suitably spaced to indicate peripheral feet per minute. A window 116 is provided in end wall 61 of housing portion 52 for viewing the indicia, as best seen in Fig. 6, said window being provided with an index mark 117.

20 The end wall 61 includes a threaded bore 118 axially aligned with shaft 103, said bore 118 carrying in threaded engagement an outer closure screw 119. When screw 119 is removed, a headed screw 120 carried by the end of shaft 103 becomes accessible for manually turning shaft 103 to axially move switch means 24 therealong to a selected position as indicated by the indicia through the window 116. In the example shown, the switch means 24 is positioned for 200 peripheral feet per minute. By turning shaft 103, any peripheral speed may be selected at which it is desired that the switch means 24 be actuated by the actuator 23.

25 To prevent rotation of switch means 24 during axial adjustment thereof, the member 104 is provided at its lower end with an axially extending groove which slidably accommodates a guide shaft 121, said guide shaft being secured at one end in plate 106 as at 122 and at the other end as at 123 in a shoulder formed on the interior surface of the housing portion 52.

30 In Fig. 5 the gear means for driving the intermittently actuated switch means 25 is illustrated. The switch means 25 includes a switch element 125 adapted to be intermittently contacted by a cam element 126 carried by a spur gear 127. The spur gear 127 is rotatably driven by a gear 128 mounted on a shaft 129 which extends between the partition 76 and the partition 67. Adjacent partition 67, shaft 129 carries a gear 130 which meshes with a pinion gear 131 carried by a shaft 132 journally mounted in partition 67. The outboard end of shaft 132 carries a gear 133 meshed with the stationary gear 86. Thus, as the housing 20 rotates, cam element 126 is likewise rotated and intermittently contacts the switch element 125 for closing switch contacts (not shown) in switch means 25.

35 The recording and marking means employed by this invention may be suitably carried or mounted in the cab of the truck, the recording means including a spring-actuated clock shown in Fig. 12 which carries a removable circular chart 140 shown in Fig. 11, the chart being rotated by the clock in a counterclockwise direction as illustrated. The chart 140 includes on its circumferential margin a plurality of radially extending spaced line segments 141 for indicating minutes. The central circular portion of the chart may provide space for pertinent information such as the time of loading, time of pour-

ing the concrete, total time of hydration and actual time the mixer was operated at the specified peripheral speed. The opposite side of the chart (not shown) may include other pertinent data to be filled in by the mixing plant inspector and job inspector, such data including the number of sacks of cement, the percentage of water in the sand, the total gallons of water, the percentage of aggregate, the water in the aggregate, the water which had been added to the mix, the mix designation, the cement brand, cement tested etc. The chart thus provides a permanent record of all pertinent data pertaining to a batch of concrete carried by the mixing truck.

In Fig. 10 is illustrated an exemplary circuit means for actuating the marking means 26 for recording on a chart 140 the time intervals or periods during which the mixer drum was rotated at a selected peripheral speed, at speeds too fast or too slow, and when the mixer was stopped.

The marking means 26 includes a first solenoid 142 having an axially movable solenoid element 143, the outer end of which may be pivotally connected intermediate the ends of marking arm 144 as at 145. The arm 144 may be pivoted about an axis at 146 and may carry at one end a suitable pencil, pen or other marking means generally indicated at 147. The arm 144 is spring-biased adjacent the other end by a spring 148 connected to said arm 144 and to a suitable member 149 which may be associated with the spring clock means.

A second solenoid 150 is provided with an axially movable solenoid element 151 which is pivotally connected as at 152 intermediate the ends of restraining arm 153 arranged transversely of the marking arm 144. One end of arm 153 may be pivotally connected at 154 to member 149, and at its other end arm 153 may be provided with a connection to a spring 155 suitably connected to the solenoid 142, the spring 155 biasing arm 153 toward the adjacent end of arm 144. Arm 153 is provided with a shoulder 156 forming a stop to limit oscillation of arm 144 when rotation of the mixing drum is too slow or too fast, and when solenoid 150 is inoperative.

Solenoid 142 is connected to the intermittently actuated switch means 25 by circuit means indicated by leads identified as 157, 157a and 157b, said circuit means including a battery source 158. The selectively actuated switch means 24 is connected with switch means 25 and the second solenoid 150 by circuit means identified by leads 159, 159a, 159b and portions of leads 157 and 157b. A light signaling means 159c may be provided in the lead 159b.

In operation, as the mixing drum rotates, the housing 20 likewise rotates because of its peripheral contact at 56 with the mixing drum. Rotation of the housing 20 causes the speed responsive means 22 to be driven through stationary gear 86 and the associated gear train in response to the speed of the mixer. Rotation of housing 20 also causes intermittent actuation of switch means 25 by cam element 126. Thus, switch means 25 is closed at intermittent intervals depending upon the speed of rotation of the housing.

When the mixing drum is rotating at selected peripheral speed, the switch actuator 23 closes switch means 24 so that solenoid element 151 of the second solenoid 150 is retracted to hold stop 156 from engagement with the end of arm 144. As the intermittently actuated switch means 25 is intermittently closed, a circuit is completed

to the first solenoid 142 whereby the solenoid element 143 is reciprocally axially movable to cause arm 144 to oscillate about pivotal axis 146 and to produce on chart 140 a relatively wide visible zigzag mark indicated at A. The wide markings at A are readily recognized and the total number of minutes during which the mixer has rotated at a selected peripheral speed may be readily computed. If the total aggregate sum of marks 10 A on the chart equal a period of from twelve to sixteen minutes, the job inspector will know that concrete in the mixing drum will have acceptable characteristics (assuming that the proper mix has been placed in the mixing drum).

15 When the speed of rotation of the mixing drum is too fast or too slow, the switch means 24 is in open position and the solenoid element 153 of the second solenoid 150 is disposed in a nonretracted position whereby stop 156 is adapted to engage the end of arm 144. Under this condition, marking arm 144 is provided a limited oscillation or swing about pivotal axis 146 each time that switch means 25 is closed by the intermittently actuating cam 126. Thus, a mark B of approximately one-half the width of the mark A is made on chart 140 and of which each complete zigzag or oscillatory cycle represents the number of peripheral feet travelled by the device in one revolution. The number of cycles in 20 a given period may be counted and the exact speed of too fast or too slow rotation computed.

25 In the event that rotation of the mixing drum is completely stopped, the switch means 24 will be in open position and the intermittently actuated switch means 24 will remain in open position. Under this condition, marking arm 144 is biased by spring 148 downwardly into a position against a stop 190 so that the marking pencil at 147 will draw a straight line indicated at 30 C on chart 140, the chart being rotated at a constant rate of speed in a counterclockwise direction by the spring actuated clock 28.

35 Thus, the chart 140 will indicate a record of conditions wherein the mixing drum is at rest, is rotated at speeds too fast or too slow, and is rotated at a selected speed. It is understood various other means may be employed for limiting oscillation of the arm 144 under various conditions of the rotation of the mixing drum.

40 The light signaling means included in the circuit provides a visible indicating means whereby the driver may know when the cement mixing drum is rotating at optimum selected speed. By this signaling device the driver's attention is directed to the maintenance of proper mixing conditions and he may thereby regulate the speed of rotation so as to rotate the mixing drum at selected speed for a selected period to arrive with properly mixed concrete on the job.

45 Installation of electrical connections between the switch means 24 and 25 carried within the rotatable housing 20 and battery and solenoid associated with the marking means is facilitated by the stationary hollow axle 71 which affords a conduit means for electrodes or other electric wire means. In the example shown, the hollow axle encloses an outer insulating sleeve 180 and a spaced inner insulating sleeve 181. Between said sleeves is provided a suitable tubular electrode 182 and within the inner sleeve 181 may be provided an electrode rod 183. The electrodes may be suitably connected to electrical wire means for making the circuit arrangement shown in Fig. 10.

50 70 75 In Fig. 14 is illustrated a different modification

of a circuit means and solenoid arrangement for producing a record as described above on a rotating time driven chart 140'.

In this modification, the actuator 23'' is adapted to contact a plurality of independently selectively adjustable switch means 191, 192 and 193, the switch means 191 being actuated when the mixing drum is rotated too fast, the switch means 192 being actuated when the mixing drum is rotated at selected speed, and switch means 193 being actuated when the drum is rotating too slow. The switch means 191, 192 and 193 may be connected to a battery 194 and to a three-stage cumulative solenoid 195 having an axially movable spring-biased solenoid element 196. The switch means 191 is connected to the first stage of the solenoid as at 197, the switch means 192 may be connected to the second stage of the solenoid as at 198 and the switch means 193 may be connected to the third stage of the solenoid as at 199.

In operation, when switch means 191 is closed, the solenoid element 196 is positioned as shown in Fig. 14 to produce a straight line indicated by E on the chart and records too fast a speed of rotation for the mixing drum. When the switch means 192 is actuated by the actuator 23'' the solenoid element 196 is moved radially inwardly of the chart to provide a mark indicated by line F which is spaced radially inwardly of mark E. When the drum is rotating too slow and switch means 193 is closed, the solenoid element 196 moves to its furthermost radially inwardly position and provides a mark indicated by line G. Thus, the total time of rotation of the drum at selected speed may be computed by adding the total number of minutes under the marks F, the total aggregate sum indicating the total time period during which the drum was rotating at selected speed.

In Figs. 12 and 13 is illustrated a circuit arrangement and a modification of the recording chart which will provide a foolproof and unchangeable accurate record of the time periods during which the cement mixer has rotated at selected desired speeds. Like parts will be given like reference numerals with a prime sign.

In Fig. 12 the selectively adjustable switch means 24' is shown prior to closing by the switch actuator 23'. The intermittently actuated switch means 25' is illustrated as closed by the cam element 126'. The chart 140' may contain on its opposite faces the pertinent data and information described with respect to the chart 140. Indicia 141' are printed on the outer circumferential margin of one face of the chart 140'.

The switch means 24' may be electrically connected to the switch means 25' by a lead 160. The switch means 25' is connected to a suitable battery 151' by a lead 161. The opposite side of the battery is connected to a lead 162 which terminates in three spaced contact points 163, 164 and 165, said contact points being disposed beneath and adjacent to the circumferential margin of chart 140'. Lead 160 is electrically connected as at 166 to a lead 167 which is connected to a spark coil 168. The spark coil 168 terminates in an element 169 directly opposed to contact point 164 and on the opposite side of the chart 140'. The switch means 24' is connected by lead 170 to spark coils 171 and 172, said spark coils 171 and 172 having an element 173 and 174 respectively directly opposed to the respective points 165 and 163 and on the side of the chart opposite to said points.

In operation it will be readily apparent that intermittent closure of switch means 25' by cam element 126' will intermittently complete a circuit between said switch means 25 and the spark coil 168 and point 164. The spark created by said circuit will burn or char, each time, a single mark such as 175 on indicia 141'. Since the rotation of cam element 126' is geared to the speed of rotation of the housing the time interval between successive closures of switch means 25' is representative of the speed of rotation of the housing and therefor of the mixing drum. Thus the single marks 175 may be spaced at different intervals on the chart; as for example, the widely spaced marks indicated by H show rotation at a slow speed, while closely spaced marks indicated at I, show rotation at a fast speed. If in the example shown intermittent closure of the switch means 25' is geared to one closure for each 100 peripheral feet per minute, the number of marks within a selected time period multiplied by 100 and divided by the minutes of the time period will give the peripheral speed of the mixing drum. When the cement mixing drum is rotating at selected speed so that the switch means 24' is closed, intermittent closure of switch means 25' will fire spark coils 168, 171 and 172 to thereby burn three radially aligned marks, such as 176, 177 and 178 on the chart. Thus, when the cement mixing drum is rotating at selected speed, the chart will be marked in a foolproof manner to indicate the time periods during which such rotation occurred.

While the modification of Fig. 12 does not show a signal light as illustrated in Fig. 10, it is understood that such a signal light may be included in the circuit arrangement.

In Fig. 15 is illustrated an exemplary circuit arrangement for utilizing the recording device described above on a stationary job site concrete mixing drum. In such a job site concrete mixer, a gate is usually provided for charging or loading the mixing drum and a discharge chute is provided for removal of the mixed concrete from the mixer. It is the purpose of this modification to describe a means and method for accurate recording all pertinent operations of a job site concrete mixer. In such a mixer, it is understood that the mixing drum is normally continuously rotating at a constant selected speed.

In Fig. 15 the circuit means is similar to that shown in Fig. 10 and has been modified to include a switch actuated by the gate and a switch actuated by the discharge chute. Interrupters are provided for oscillating the marking arm under such conditions to provide a distinctive, easily recognizable mark on the chart.

The circuit means includes a selectively adjustable switch means 200 adapted to be closed at selected speed by a speed responsive actuator 201, an intermittently actuated switch means 202 adapted to be closed intermittently by a rotatable cam element 203, a battery source 205, a light signal 205, a first solenoid 206 having an axially movable solenoid element 207 and a second solenoid 208 having an axially movable solenoid element 209 all arranged as in the first described embodiment. The solenoid element 207 is pivotally connected at 210 to a pivoted marking arm 211 which carries at one end a marking means generally indicated at 212. A chart 213 is rotatably driven by suitable time means in counterclockwise direction and is provided with indicia 214 spaced to measure minute

intervals. The solenoid element 209 is pivotally connected at 215 to a restraining arm 216 which is provided with a shoulder 212 for limiting oscillation of the marking arm 211 in one position as described in the first embodiment. The marking arm 211 is spring-biased by a spring 218 and the restraining arm 216 is biased by a spring 219.

A gate switch 220 is mounted adjacent a movable gate to the mixing drum for actuation by said gate. When the gate is closed for a mixing operation of the drum, the gate switch 220 is in the position illustrated in Fig. 15 and provides a completed circuit between the switch means 202, battery 204 and solenoid 206 as identified by leads 221, 222, 223 and 224. In gate closed position, gate switch 220 provides a circuit including the intermittently actuated switch means 202 for intermittent oscillation of the marking arm 211 by the first solenoid 202.

The discharge chute, when in closed position or in a position when the mixing drum is operating to mix a batch of concrete, is adapted to close a discharge chute switch means 225 so as to permit normal actuation of the marking arm 211 for recording a selected speed, too fast or too slow speeds, and a stop condition as described in the first embodiment. In closed position, switch means 225 provides a circuit through leads 226, 221, 222, 223, 224 and 227 for permitting operation of solenoid 206 by the intermittently actuated switch means 202.

Thus, the circuit means shown in Fig. 15 will permit operation of the solenoids 206 and 208 in the manner described in the first embodiment whereby rotation of the mixer at selected speed will be identified by marks A' on chart 213, rotation of marks at too fast or too slow a speed will be identified by marks B' on chart 213 and when the mixer is not rotating, a straight line mark will be provided on chart 213 as indicated by mark C'.

When the concrete mixing drum is being rotated and the gate is in open position, the gate switch means 220 is actuated into the position indicated by phantom lines at 228 and opens the circuit for actuation of switch means 202 and closes a circuit for bringing into operation a suitably selected interrupter means 229, the interrupter means 229 providing rapid oscillation of marking arm 211. The rapid oscillation of marking arm 211 provides a narrow, dense mark on chart 213 as indicated at K. The number of minutes covered by mark K will indicate the amount of time that the mixer was being charged.

When the concrete has been mixed and the discharge chute lowered to discharge the concrete from the mixer, the switch means 225 will be moved to the position indicated by phantom lines at 230. In this position, the discharge switch means opens the circuit which includes the intermittently actuated switch 202 and closes a circuit containing suitable interrupter means 231. The interrupter 231 causes rapid oscillation of the solenoid element 207 to rapidly oscillate marking arm 211 to provide a dense narrow mark indicated by L on chart 213. Since the interrupters are selected with different interrupter frequency characteristics the marks K and L will appear as different marks both in density and in width so as to be readily recognized.

It is assumed in the above explanation of the operation of the circuit means that the mixing drum is not rotating at selected speed. A suit-

able gang switch means (not shown) may be provided adjacent to the gate switch means 220 and the discharge chute means 225 for opening and closing the circuit which includes the selectively actuated switch means 200.

It should be noted that in the marks B' and B shown in the first embodiment, the number of oscillations within the interval between minute indicium indicates the speed at which the mixing drum was rotated. For example, if the peripheral speed of the mixing drum was 100 feet per second, and the cam element 203 was geared to actuate the switch means 202 for each revolution, when the selected speed was 200 feet per minute, there would be two zigzag cycles within the interval between adjacent minute indicia on the chart. If the speed of rotation of the mixer was considerably less, the zigzag cycle would be greatly extended so that the number of oscillations divided by the number of minutes covered by the zigzag line would give the speed of the mixing drum over a specified time period. When the mixing drum was rotating too fast or over 200 peripheral feet per minute, the zigzag line would be relatively dense as indicated at M, and counting the number of zigzag cycles within the selected time period would indicate how fast the mixing drum was rotating.

It should also be noted that the speed responsive actuator may be provided with a flattened circumferential portion adapted to maintain contact with the switch means 24 over a practical range of selected peripheral speeds, as for example, 195 to 205 peripheral feet per minute. Mixing of concrete within this exemplary range for practical purposes will produce acceptable concrete.

It is understood that suitable means may be provided for breaking the circuit to the marking means in the event the drum should come to rest with one or both of the switch means in closed position, such a closed circuit condition having detrimental effect on the solenoids of the marking means.

It will thus be readily apparent to those skilled in the art that a means and method have been provided by the above-described device which will accurately record data concerning mixing conditions taking place in a cement mixing drum carried by a truck while in transit between a proportioning plant and a job. Such a device provides a record of mixing conditions which has not heretofore been attained. The advantages of recording the exact mixing conditions while the truck is in transit not only insures that only acceptable concrete is provided for the job, but also results in saving time since the driver may make certain that the concrete is properly mixed when he reaches his destination.

It is understood that other modifications and changes may be made in the device described above and all such modifications coming within the scope of the appended claims are embraced thereby.

We claim:

1. In a device for measuring and recording mixing conditions for a rotatable concrete mixing drum, the combination of: a pivotally mounted rotatable hollow housing; spring means for biasing said housing into rolling engagement with a periphery of said drum; speed responsive means operable within said housing and including an axially movable switch actuator member; a movable record chart provided with time indicia; time means for moving said chart; mark-

ing means for said chart; and circuit means including switch means within said housing intermittently actuated by rotation of said housing into closed position, adjustably positioned switch means carried within said housing in cooperable relationship to said actuator member and adapted to be closed thereby when the housing is rotating at a preselected speed, and solenoid means electrically connected to both switch means for oscillating said marking means when both switch means are in closed position.

2. In a device for measuring and recording mixing conditions for a rotatable concrete mixing drum, the combination of: a pivotally mounted rotatable hollow housing; spring means for biasing said housing into rolling engagement with a periphery of said drum; speed responsive means operable within said housing and including an axially movable switch actuator member; a movable record chart provided with time indicia; time means for moving said chart; marking means for said chart; and circuit means including switch means within said housing intermittently actuated by rotation of said housing into closed position, adjustably positioned switch means carried within said housing in cooperable relationship to said actuator member and adapted to be closed thereby when the housing is rotating at a preselected speed; said marking means being operably connected to both switch means for distinctively marking said chart when both switch means are closed for indicating time intervals when the mixing drum is rotated at selected speed.

3. A device as claimed in claim 2, wherein the adjustably positionable switch means is axially movable parallel to the actuator member.

4. A device as claimed in claim 2, wherein indicia means are cooperably associated with the adjustably positionable switch means for indicating the position of said positionable switch means with respect to the actuator member.

5. A device as claimed in claim 2, wherein the marking means includes a plurality of radially aligned spark coils adjacent to one face of the chart and respectively opposed contact points adjacent to the opposite face of the chart for burning a mark on said chart when both said switch means are closed.

6. In a device for recording mixing conditions of a concrete mixing drum including a housing adapted to be rotated by said drum, means operable within said housing in response to the speed of rotation of said drum, and a rotatable time driven chart, the provision of: a switch actuator member movable by said speed responsive means; a switch means adjustably movable in relation to the switch actuator member and cooperable therewith to be closed when the drum is rotated at a preselected speed; a second switch means normally in open position and intermittently actuated to closed position; marking means for the chart movable transversely thereof when both switch means are in closed position; and means electrically connecting both said switch means and marking means.

7. A device as defined in claim 6, wherein the marking means includes a marking arm, a spring biasing said marking arm into one position and a solenoid means connected to said marking arm for oscillating said arm.

8. In a device for recording mixing conditions of a concrete mixing drum including a housing adapted to be rotated by said drum, means operable within said housing in response to the speed

of rotation of said drum, and a rotatable time driven chart, the provision of: a switch actuator member movable by said speed responsive means; a switch means adjustably movable in relation to the switch actuator member and cooperable therewith to be closed when the drum is rotated at a preselected speed; a second switch means normally in open position and intermittently actuated to closed position; marking means including spark means adjacent to said chart and energized by closure of said switch means; and means electrically connecting both said switch means and marking means.

9. In a device for recording mixing conditions of a concrete mixing drum including a housing adapted to be rotated by said drum, means operable within said housing in response to the speed of rotation of said drum, and a rotatable time driven chart, the provision of: a switch actuator member movable by said speed responsive means; a switch means adjustably movable in relation to the switch actuator member and cooperable therewith to be closed when the drum is rotated at a preselected speed; a second switch means normally in open position and intermittently actuated to closed position; marking means including a plurality of radially aligned spark means disposed adjacent to said chart, one of said spark means being energized when said second switch means is actuated to closed position and the other spark means being energized when the adjustably movable switch means is actuated to closed position, whereby a plurality of radially aligned burned marks are made on said chart for indicating time periods when the drum is rotating at selected speed; and means electrically connecting both said switch means and marking means.

10. In combination with a mixing drum, a device for recording mixing operations of said drum including a housing adapted to be rotated by said drum, means operable within said housing in response to the speed of rotation of said drum, a rotatable time-driven chart, said drum including a charging gate and a discharge chute, the provision of: a switch actuator member movable by said speed responsive means; a first switch means adjustably movable in relation to the switch actuator member and cooperable therewith to be closed when the drum is rotated at a preselected speed; a second switch means normally in open position and intermittently actuated to closed position by rotation of said housing; marking means disposed adjacent to said chart and normally adapted to be oscillated by intermittent closure of said second switch means to mark said chart in accordance with the speed of rotation of said drum, said marking means being operable when said second switch means and said first switch means are closed to indicate on said chart rotation of the drum at selected speed; interrupter means and gate operated switch means; a second interrupter means and a discharge chute operated switch means; circuit means to electrically connect said switch means and interrupter means; said gate operated switch means in one position closing a circuit between said intermittently actuated switch means and the marking means, and in another position closing a circuit for said interrupter means and said marking means whereby said marking means is rapidly oscillated when the charging gate is opened; said discharge chute operated switch means in one position closing a circuit between said intermittently

actuated switch means and said marking means and in another position closing a circuit between said marking means and the second interrupter means whereby said marking means is oscillated to indicate on said chart the time period during which the discharge chute is in discharge position.

11. In a device for measuring and recording mixing conditions for a rotatable mixing drum, the combination of: a hollow housing; speed responsive means operable within said housing and including an axially movable switch actuator member; a rotatable record chart provided with time indicia; time means for rotating said chart; marking means for said chart; and circuit means including switch means within said housing intermittently actuated into closed position in response to the speed of rotation of the mixing drum, adjustably positioned switch means carried within said housing in cooperable relationship to said actuator member and adapted to be closed thereby when the mixing drum is rotating at pre-selected speed; said marking means being operably connected to both switch means for marking said chart in response to closure of each switch means for indicating time intervals when the mixing drum is rotated at selected speed and at speeds slower and faster than selected speeds.

12. A device as recited in claim 11 wherein the marking means includes a marking arm, a spring biasing said marking arm into one position; a solenoid means connected to said marking arm for oscillating said arm, and stop means cooperable with said marking arm for limiting oscillation thereof.

13. A device as recited in claim 12 wherein a

5

solenoid means is connected to said stop means, said latter solenoid means being actuated by said switch actuator member to release said marking arm from engagement with said stop means for producing a distinctive mark on said chart when the mixing drum is rotated at selected speed.

14. In a device for recording mixing conditions for a rotatable mixing drum, the combination of: recording means for intelligibly indicating selected conditions of rotation of said mixing drum; means responsive to rotation of said drum and positioned adjacent thereto, said responsive means including a first normally open switch means and actuating means therefor to intermittently close said switch means in response to each revolution of said drum; adjustably positioned second normally open switch means and actuating means therefor responsive to the speed of rotation of said drum and to close the second switch means at a preselected speed of rotation of the drum; and circuit means operably connecting said first and second switch means and said recording means for recording in response to closed positions of each of said switch means.

RAYMOND G. OSBORNE.
ROBERT O. BOYKIN.
